UNITED STATES PATENT OFFICE.

HENRY UNDERWOOD, OF TOLLAND, CONNECTICUT.

IMPROVEMENT IN DOOR-LATCHES.

Specification forming part of Letters Patent No. 44,476, dated September 27, 1864.

To all whom it may concern:

Be it known that I, HENRY UNDERWOOD, of Tolland, in the county of Tolland and State of Connecticut, have invented a new and Improved Door-Latch; and I do hereby declare that the following is a full, clear, and exact description thereof, which will enable others skilled in the art to make and use the same, reference being had to the accompanying drawings, forming part of this specification, in which—

Figure 1 represents a horizontal section of my invention, taken in the line *x x*, Fig. 2; Fig. 2, a longitudinal vertical section of the same, taken in the line *y y*, Fig. 1; Fig. 3, an outer side view of the same, the knob-arbor being in section, as indicated by the line *z z*, Fig. 1.

Similar letters of reference indicate like parts.

This invention relates to a new and improved door-latch of that class which have sliding bolts; and it consists in applying the knob-arbor to the bolt, and also constructing the knob-arbor in such a manner that the use of a spring is avoided and the bolt made to operate equally as well as if a spring were employed.

A represents the sliding bolt, which is fitted in a horizontal mortise, *a*, in the door, and is beveled at its outer end, as usual, as shown at *b*, Fig. 1, to admit of passing into the strike or nosing *B* when the door is closed.

C represents the knob-arbor, which passes horizontally through the door, just above the back part of the bolt *A*, and is composed of two parts, *c c'*, each of which is in the form of a crank, as shown clearly in Fig. 1, each part having a knob, *D*, on its outer end.

The two parts *c c'* of the knob-arbor are connected as follows: The part *c* at its inner end is made of cylindrical form, as shown at *d*, and has a plate, *e*, projecting radially from it of sufficient length to fit into a recess, *f*, in the upper side of the bolt near its back end. (See more particularly Fig. 2.) The inner end of the part *c'* of the knob-arbor is made in the form of a tube, *g*, and this tube *g* has a longitudinal slot, *h*, made in it to receive the plate *e*, the slot being wider than the thickness of the plate to admit of the plate *e* being moved or shoved back, and the cylindrical end *d* of

the part *c* of the knob-arbor being turned a certain distance without affecting the part *c'* of the knob-arbor.

In consequence of having the two parts *c c'* of the knob-arbor in the form of cranks, the knobs *D* are made to serve as weights, the knob of the part *c* causing the bolt *A* to be forced out from the mortise *a* as far as it is designed to move, the part *c* resting on a stop, *i*, on a plate, *j*, at the outer side of the door. The part *c'* of the knob-arbor rests upon a similar stop, *k*, which keeps the tube *g* in such a position that the plate *e* of *c* will be in contact with the front edge of the slot *h* of tube *g*. (See Fig. 2.)

From the above description it will be seen that in order to draw the bolt *A* inward and free from the strike or nosing, either of the knobs *D* are raised, which causes the plate *e* to act upon the bolt *A* and move back the bolt; and it will further be seen that when the door is drawn to a closed state with the hand, grasping the knob on the part *c'* of the arbor, the bolt *A* will, as its beveled end comes in contact with the strike or nosing, be forced back without turning the part *c'*, owing to the play of the plate *e* in the slot *h* of the tube *g*. Thus it will be seen that I avoid the use of a spring, the gravity of the knobs being made to answer instead, and at the same time the bolt is allowed in closing the door to be forced back without turning the knob, which is grasped by the hand.

I am aware that the crank-knob is in common use on the spring door-latch, it being applied for the purpose of removing the knob farther from the edge of the door, so as to prevent the knuckles of the hand being injured as the door is drawn to or closed from without; but this application or device throws so much more weight or work on the spring, causing it soon to lose its vitality. In my application of the crank-knob it has the above-named advantages without its disadvantage. It can also be applied to sash-doors where the bolt must be short, the crank taking the knob from the edge of the door just so far as may be desirable.

I claim as new and desire to secure by Letters Patent—

1. The crank-shaped knob-arbor *C*, provided with the plate *e*, in combination with the slide-

bolt A, arranged substantially as and for the purpose herein set forth.

2. Constructing the knob arbor C of two parts, c c', one part, c, being of cylindrical form at its inner end, d, and having the plate e projecting from it, and the other part, c', having a tube, g, at its inner end provided with a slot,

h, to receive the inner end, d, and plate e of the part c, all arranged to operate substantially as and for the purpose set forth.

HENRY UNDERWOOD.
